Graham & Harris
ATTORNEYS.

UNITED STATES PATENT OFFICE.

JOHN L. MORRIS, OF LOS ANGELES, CALIFORNIA.

DIE FOR CASTING BEARING LINERS.

Application filed September 7, 1921, Serial No. 498,978. Renewed May 5, 1924.

To all whom it may concern:

Be it known that I, JOHN L. MORRIS, a citizen of the United States, residing at Los Angeles, in the county of Los Angeles and State of California, have invented a new and useful Die for Casting Bearing Liners, of which the following is a specification.

This invention relates to the art of casting metallic objects in steel dies for the purpose of producing a casting which will adhere sufficiently closely to a predetermined size and be of such a finish that it may be put into use without machining or further mechanical attention, and relates particularly to the casting of bearing liners.

In the present methods of die casting bearing liners a certain porosity of the casting results from the fact that the molten metal is introduced into the matrix suddenly and in a turbulent condition which does not allow the entrained air and gases to separate from the body of molten metal and consequently the metal solidifies with certain portions thereof in a sponge-like condition.

It is an object of my invention to provide a die in which the molten metal is first introduced into a surge chamber in which the entrained gases may separate from the body of molten metal and the metal may then flow horizontally and quietly into the matrix.

It is a further object of my invention to provide a die of this type from which the casting may be easily removed.

Other objects and advantages will be made evident hereinafter.

Referring to the drawing which is for illustrative purposes only:

Fig. 1 is a perspective view of a bearing liner cast in a die embodying my invention.

Fig. 2 is an elevation of the die employed to cast the liner shown in Fig. 1, the upper portion of the die being shown in section to illustrate the interior construction.

Fig. 3 is a fragmentary section upon a plane represented by the line 3-3 of Fig. 2.

Fig. 4 is a vertical cross section taken on a plane represented by the line 4-4 of Fig. 2.

Upon a base block 11 I mount a column 12 having formed therein a channel 13 forming a pouring spout, the column being secured upon the block 11 by cap screws 14.

Centrally from the upper surface 15 of the block 11 is raised a substantially semicircular core 16 extending from the end 17 of the block 11 to a point 18 adjacent to the column 12. Near the end 19 of the core 16 is formed a recess 20 presenting the inner contour 21 of the liner 22 shown in Fig. 1. Over the core 16 is placed a cap 30 fitting closely against the front face of the column 12 and the sides 32 of which fit closely down against the surface 15 of the block. This cap 30 is contoured to produce the outer formation 36 of the liner 22.

When the cap 30 is in place upon the block 11, a surge chamber 40 having communication with the spout 13 is formed between the column 12 and the end 19 of the core 16. Molten bearing metal 39 poured into the spout 13 from a ladle or other suitable means collects in the surge chamber 40 and therein the gases carried with the molten metal and generated from such impurities as may be present are allowed to separate therefrom before the metal flows through the horizontal passages between the surge chamber and the matrix formed by relieving the dividing wall 50 in the manner indicated at 51. The level 55 of the metal 39 will mount at a constant rate in both the chamber 40 and the matrix as the molten metal is poured in through the spout 13 and after the level passes the top of the passage between the chamber and the matrix, the small amount of gas arising from the metal 39 within the matrix is passed off through the vent risers 58.

It will be perceived that the construction of this die also allows the cap 30 and the casting 22 to be freely removed from off the core 16 without interference from the presence of the body of metal in the surge chamber 40, and that the elimination of turbulence in the molten metal within the matrix results in a product having a very fine texture which is especially desirable in bearings.

I claim as my invention:

A die for forming hollow semi-cylindrical objects comprising walls forming a cavity having the shape of the desired object, the axial plane defining the edges of the semi-

cylindrical object being substantially horizontal; and walls forming a vertical channel extending from said plane upwardly through the top of the mould, the substance 5 of the mould being cut away to provide an open communication between said vertical column and the end of said cavity, the openings between said channel and said cavity

extending from a point in said plane to a point at or near the highest point of said 10 cavity.

In testimony whereof, I have hereunto set my hand at Seattle, Washington, this 26th day of August, 1921.

JOHN L. MORRIS.
